[57] CLAIM

The ornamental design for a belt pouch, as shown and described.

DESCRIPTION

FIG. 1 is a front view of a first embodiment of the pouch showing my new design;

FIG. 2 is a left side view thereof;

FIG. 3 is a top view thereof;

FIG. 4 is a bottom view thereof;

FIG. 5 is a back view thereof;

FIG. 6 is a left end view thereof;

FIG. 7 is a front view of the pouch in a fully opened condition;

FIG. 8 is a back view of the pouch in a fully opened condition;

FIG. 9 is a top view of the pouch in a fully opened condition;

FIG. 10 is a bottom view of the pouch in a fully opened condition;

FIG. 11 is a right side view of the pouch in a fully opened condition;

FIG. 12 is a left side view of the pouch in a fully opened condition;

FIG. 13 is a front view of another embodiment of the pouch showing my new design;

FIG. 14 is a left side view of the embodiment of FIG. 13;

FIG. 15 is a top view of the embodiment of FIG. 13;

FIG. 16 is a bottom view of the embodiment of FIG. 13;

FIG. 17 is a back view of the embodiment of FIG. 13;

FIG. 18 is a left side view of the embodiment of FIG. 13;

FIG. 19 is a front view of the embodiment of FIG. 13 in a fully opened condition;

FIG. 20 is a back view of the embodiment of FIG. 13 in a fully opened condition;

FIG. 21 is a top view of the embodiment of FIG. 13 in an opened condition;

FIG. 22 is a bottom view of the embodiment of FIG. 13 in an opened condition;

FIG. 23 is a right side view of the embodiment of FIG. 13 in an opened condition; and,

FIG. 24 is a left side elevation of the embodiment of FIG. 13 in an opened condition.
